[57] CLAIM

The design for a loader bucket, as shown and described.

DESCRIPTION

FIG. 1 is a front perspective view of a loader bucket embodying our new design;

FIG. 2 is a rear perspective view thereof;

FIG. 3 is a top plan view thereof;

FIG. 4 is a bottom plan view thereof;

FIG. 5 is an enlarged front elevational view thereof;

FIG. 6 is an enlarged rear elevational view thereof;

FIG. 7 is a further enlarged right side elevational view thereof;

FIG. 8 is a further enlarged left side elevational view thereof; and,

FIG. 9 is a further enlarged transverse sectional view thereof, taken on line 9—9 in FIG. 3.
